UNITED STATES PATENT OFFICE

GUSTAVE RICARD ANDERSON, OF CAMBRIDGE, MINNESOTA

DESIGN FOR AN EMBLEM

Application filed February 9, 1933. Serial No. 47,167. Term of patent 14 years.

To all whom it may concern:

Be it known that I, GUSTAVE RICARD ANDERSON, a citizen of the United States, residing at Cambridge, in the county of Isanti and State of Minnesota, have invented a new, original, and ornamental Design for an Emblem, of which the following is a specification, reference being had to the accompanying drawing, forming part thereof.

The figure is a perspective view of an emblem, showing my new design.

I claim:

The ornamental design for an emblem, as shown.

GUSTAVE RICARD ANDERSON.
